(57) **CLAIM**

The ornamental design for collapsible cap for a pickup truck, as shown and described.

DESCRIPTION

FIG. 1 is a rear perspective view of a collapsible cap for pickup a truck showing my new design;

FIG. 2 is a rear perspective view of a collapsible cap for pickup a truck showing an alternate position of use;

FIG. 3 is a top view of a collapsible cap for pickup a truck;

FIG. 4 is a rear view of a collapsible cap for pickup a truck;

FIG. 5 is a left view of a collapsible cap for pickup a truck;

FIG. 6 is a right side view of a collapsible cap for pickup a truck; and,

FIG. 7 is a front end view of a collapsible cap for pickup a truck.

The broken line showing of a truck in FIGS. 1 and 2 forms no part of the claimed design.
